FIG. 1 is a side elevational view of a reed for a reed switch assembly;

FIG. 2 is an end view thereof;

FIG. 3 is a bottom plan view thereof;

FIG. 4 is a top plan view thereof;

FIG. 5 is a side elevational view of a modified form of the reed described in FIG. 1 showing our new design;

FIG. 6 is an end view thereof;

FIG. 7 is a bottom plan view thereof;

FIG. 8 is a top plan view thereof;

FIG. 9 is a side elevational view of a modified form of the reed described in FIG. 1 showing our new design;

FIG. 10 is an end view thereof;

FIG. 11 is a bottom plan view thereof;

FIG. 12 is a top plan view thereof;

FIG. 13 is a side elevational view of a modified form of the reed described in FIG. 1 showing our new design;

FIG. 14 is an end elevational view thereof;

FIG. 15 is a bottom plan view thereof;

FIG. 16 is a top plan view thereof;

FIG. 17 is a side elevational view of a modified form of the reed described in FIG. 1 showing our new design;

FIG. 18 is an end elevational view thereof;

FIG. 19 is a bottom plan view thereof;

FIG. 20 is a top plan view thereof;

FIG. 21 is a side elevational view of a modified form of the reed described in FIG. 1 showing our new design;

FIG. 22 is an end elevational view thereof;

FIG. 23 is a bottom plan view thereof;

FIG. 24 is a top plan view thereof.

The end opposite to the ends shown in FIGS. 2, 6, 10, 14, 18 and 22 are identical with these figures respectively. The ends are shown fragmentary on one end and broken away at the other end to show indeterminate length. The sides opposite to the sides shown in FIGS. 1, 5, 9, 13, 17 and 21 are mirror images of these figures respectively.

We claim:

The ornamental design for a reed for a reed switch assembly, as shown and described.
